United States Patent Office.

JOHN B. VALLIQUETTE, OF CHICAGO, ILLINOIS.

Letters Patent No. 76,560, dated April 7, 1868.

IMPROVEMENT IN BRIDGES.

The Schedule referred to in these Letters Patent and making part of the same.

TO ALL WHOM IT MAY CONCERN:

Be it known that I, JOHN B. VALLIQUETTE, of Chicago, in the county of Cook, in the State of Illinois, have invented an Improved Gate for Swing-Bridges; and I do hereby declare that the following is a full and exact description thereof, reference being had to the accompanying drawings, and to the letters of reference marked thereon, making a part of this specification, in which—

Figure 1 is a plan view of my invention, with the bridge partially turned.

Figure 2, an elevation of the gate in position for use.

Figure 3, a plan view of the same.

The nature of my invention consists in the use of a gate, attached to a truck, made to run transversely with and below the road bed, of such a width as will place the wheels such a distance from the slot in which the gate runs as will prevent it from being obstructed with ice and dirt; and in the arrangement of vertical rollers attached to the ends of the gates, and a projection at both ends of the bridge, for opening them when the bridge is being shut; and further, in the use of rubber bumpers, fitted in the ends of the slots in which the gates run, to prevent them, when closed by their respective weights, from striking so hard against the framework as to cause injury.

In order to give a correct understanding of my invention, I have marked corresponding parts with similar letters, and will now give a detailed description.

A represents a common swing-bridge, and B B the roadways leading to and from it. P P R represent a common trestle-work at the ends of the bridge, and is made double its width, in order that gates G G may open clear of the roadways B B, the timbers R R being bolted fast to the piles P, for the purpose of supporting a track, K, made of iron, and used for the truck J to run on. The piles are made to project above the track K, and to the roadways B B, at which point they are covered with plank, or pavement, as the case may require, except the slots H H, made for the gates to slide in, but not large enough to interfere with travel, the sides being protected from wear by means of metal strips, fastened in any desirable manner.

J, figs. 2 and 3, represents one of the trucks, which is arranged to run on the track K, and support a gate, G, projecting far enough above the roadway B to prevent teams and foot-passengers from passing when it is shut. It will be seen at fig. 3 that the truck J is made to run on a wide track; this is for the purpose of protecting the wheels a from ice and dirt, which must necessarily fall through the slots H, and would, if allowed to fall on the track, impede the operating of the gate. The truck is made of iron, and as light as will support a gate of metal, and has a rope, L, attached to it, and passing over a pulley, N, and connecting with a weight, M, for drawing the gate together when the bridge is being opened. Friction-rollers, f, are to operate on the edges of the gates, against which projections e e on the railing D of the bridge are made to strike when being turned. X X represent blocks of rubber fitted in the ends of slots H, for the purpose of breaking the concussion of the gates when being closed by the weights M.

Operation.

Fig. 1 represents the gates partly open, as when the bridge is swung for foot-passengers only. The gates will, however, open the entire width of the roadway as the bridge is swung further around, but will close as soon as the projections e pass the railings I, between the roadways B B and platforms C C, fig. 1. Care must always be taken to swing the bridge in the direction indicated by arrow W.

Having thus fully described my invention, what I claim, and desire to secure by Letters Patent, is—

The gates G G, arranged to run in slots H H, in combination with the trucks J J, projections e e, and rubber blocks X X, substantially as and for the purpose set forth.

J. B. VALLIQUETTE.
